PROCESS FOR DEHYDROGENATING
HYDROCARBONS

Robert G. Atkinson, Sunray, Tex., assignor to
The Shamrock Oil and Gas Corporation, Amarillo, Tex., a corporation of Delaware

No Drawing. Continuation of application Serial No. 375,013, January 18, 1941. This application January 10, 1942, Serial No. 426,348

3 Claims. (Cl. 260—683)

This invention relates to thermal conversion processes for hydrocarbons, and relates more particularly to a method and catalyst for dehydrogenating low molecular weight hydrocarbons.

The production of olefins or unsaturated hydrocarbons from low molecular weight saturated hydrocarbons such as butane, propane, etc., is of great commercial importance. The olefinic material thus produced, which normally comprises butylenes and propylene, is directly accessible for the production of high octane gasoline or aviation fuel by either polymerization or alkylation processes. By segregation of isobutylene it is possible by processing it further by such methods as are mentioned above to produce iso-octane, which is a very valuable anti-knock motor fuel blending material. Also, the olefinic material, being relatively active from the chemical standpoint, affords a suitable starting point for the synthesis of many chemical products, including alcohols, glycols, chlorinated material, and the like.

It is possible to subject butane to cracking temperatures and secure appreciable yields of propylene and butylene. This purely thermal type of process is occasionally practiced on commercial scale. However, the yield of unsaturates in the purely thermal process as it has been proposed and carried out is not as high as is desirable, and a considerable quantity of the hydrocarbons undergoing cracking is converted into saturated, lower molecular weight hydrocarbons, such as propane, ethane, or methane, which are undesirable by-products of the cracking reaction.

It is the principal object of the present invention to increase the yield of olefinic hydrocarbons, typically propylene and butylene, obtainable from a cracking of paraffin hydrocarbons, as, for example, butane.

Catalytic dehydrogenitic processes have been developed in which the gaseous hydrocarbons are passed over a catalytic contact mass maintained at high temperature, and by such means increased yields of unsaturates and a decreased conversion into undesired by-products may be obtained. However, the activity of such catalytic masses depends upon the condition of the surface, which in use tends to become rapidly masked or coated over or otherwise rendered inert so that the process must be repeatedly shut down for reactivation of the catalyst. Also, complex and expensive equipment is required for carrying out such cracking processes under optimum conditions.

It is an object of the present invention to pro-

vide a method and a catalyst for the dehydrogenation of hydrocarbons in which fresh catalyst is continually fed into the reaction zone, thereby maintaining a constant and undiminished catalytic activity productive of high yields of the desired olefins.

Broadly speaking, the present invention comprises the addition of small amounts of organo-metallic compounds, as, for example, chromium naphthenates, to the hydrocarbon material undergoing dehydrogenation. By this method I find it possible to increase the yield of unsaturates and decrease the amount of undesirable by-products which are normally formed.

I prefer to use tin or chromium naphthenates, which I find to give the best results with low molecular weight hydrocarbons such as butane. These naphthenate catalysts may be variously introduced into the reaction zone, provided that they are introduced in a more or less continuous manner. The most convenient and preferable method is to dissolve the naphthenate in the relatively small proportion required for catalysis in the charging stock while the latter is maintained in the liquid state, and then to feed this solution into cracking tubes heated to the desired cracking temperature.

In general, I prefer to employ only moderate pressures in the cracking zone, for example, 20 pounds per square inch, and under these conditions the dehydrogenating reaction takes place largely in the vapor phase, particularly when dealing with low molecular weight hydrocarbons such as butane at cracking temperatures in excess of 1000° F., as hereinafter described.

If an organo-metallic catalyst is employed which is volatile under the conditions prevailing in the cracking zone, the catalyst will, of course, traverse the cracking zone in vapor form, along with the hydrocarbon vapors. When employing less volatile organo-metallic compounds as the catalyst, such a catalyst may traverse the cracking zone as a fog, mist, or dust borne by the hydrocarbon vapors.

There may be a slow accretion of catalyst on the walls of the cracking tube, but in general I find that a very substantial proportion of the metal employed is recoverable from the hydrocarbon effluent, as when employing tin or chromium naphthenate as the catalyst. The recovery and recirculation of the catalytic material in a form which may be added to further hydrocarbon charge stock are within the scope of the present invention.

Among the advantages arising from the prac-

tic of the present invention are the very substantially increased yields of olefinic material, the great simplicity of the process, which necessitates no expensive equipment, and the possibility of recirculating the catalytic material.

Further objects and aspects of the invention will become apparent from the following description and discussion of specific examples.

In general, the following experiments were performed in an experimental cracking still in which a horizontal cracking tube constructed of 2½% chromium alloy steel was employed. This tube had an internal diameter of 3 inches and a length of about 72 inches and was heated by being positioned in a gas fired furnace. The 15 butane charging stock was pumped into a run of 1½ inch pipe, approximately twice the length of the cracking tube, which was positioned over the cracking tube and served as a vaporizer and preheater. The preheated stream of vapors were 20 then introduced downwardly into one end of the cracking tube proper, while the effluent gases were removed from the opposite end of the cracking tube.

RUN 1.—No catalytic material added

The preheater tube and cracking tube situated as described above in the experimental cracking still were cleaned before starting the experiment by blowing air through them while they were held at a temperature of 1000° F. The charge tank for the equipment was filled with essentially pure N-butane which was then pumped out of the tank and passed through the preheater tube and thence through the cracking tube at a rate of about 135 space velocities per hour. The cracking tube was maintained at a temperature of 1065° F. throughout the experiment and the pressure in the reaction zone of the tube was held at 20 pounds per square inch by means of a back pressure valve on the outlet. The analysis of the effluent gases issuing from the tube was as follows:

Hydrogen	Methane	Ethylene	Ethane	Propylene	Propane
Per cent	Per cent	Per cent	Per cent	Per cent	Per cent
3.30	10.03	5.93	10.37	11.53	1.43

Iso-butylene	Butylene	Iso-butane	Uncracked normal butane
Per cent	Per cent	Per cent	Per cent
0.69	2.07	0.30	54.35

Stoichiometric calculations show that the following products were formed per each 100 mols of butane decomposed:

Hydrogen	Methane	Ethylene	Ethane	Propylene	Propane
Mols	Mols	Mols	Mols	Mols	Mols
14.22	43.22	25.55	44.69	49.69	6.16

Iso-butylene	Normal butylene
Mols	Mols
2.97	8.92

RUN 2.—Chromium naphthenate

The charge tank of the experimental cracking still was filled with normal butane and 4.17 grams of chromium naphthenate per gallon of butane

was dissolved in the charge by adding the naphthenate to the tank and then circulating normal butane through the tank until the chromium naphthenate was entirely dissolved. The normal butane was cracked by pumping it through the experimental still in exactly the same manner as was described in "Run 1," the tube being maintained at a temperature of 1065° F. by means of external firing throughout the experiment. The cracked gases issuing from the cracking tube had the following analysis:

Hydrogen	Methane	Ethylene	Ethane	Propylene	Propane
Per cent	Per cent	Per cent	Per cent	Per cent	Per cent
6.60	2.70	3.59	4.24	7.44	1.04

Iso-butylene	Butylene	Uncracked normal butane
Per cent	Per cent	Per cent
0.37	3.57	70.45

In addition to these cracked gases 250 cc. of aromatic liquid polymer was produced per each thousand cubic feet of normal butane charged. Stoichiometric calculations show that, in addition to the liquid polymer, the following products were formed per each 100 mols of butane decomposed:

Hydrogen	Methane	Ethylene	Ethane	Propylene	Propane
Mols	Mols	Mols	Mols	Mols	Mols
44.36	18.15	24.13	28.50	50.01	6.99

Iso-butylene	Butylene
Mols	Mols
2.49	24.00

RUN 3.—Tin naphthenate

The charge tank of the experimental still was filled with N-butane and 6.08 cc. of commercial tin naphthenate per gallon of butane was dissolved in the charge stock by means of circulation out of the bottom and into the top of the tank. The charge stock was then pumped through the heated cracking tube where it was held at a pressure of 20 pounds per square inch and a temperature of 1065° F. in exactly the same manner as described in "Run 1." The analysis of the cracked gases issuing from the tube was as follows:

Hydrogen	Methane	Ethylene	Ethane	Propylene	Propane
Per cent	Per cent	Per cent	Per cent	Per cent	Per cent
7.40	1.58	2.38	4.65	7.69	1.19

Iso-butane	Iso-butylene	Normal butylene	Uncracked normal butane
Per cent	Per cent	Per cent	Per cent
0.50	0.45	4.36	69.80

In addition to the cracked gases 3700 cc. of aromatic liquid polymer was formed per each thousand cubic feet of butane vapors passed through the furnace. Calculations show that, in addition to the liquid polymer, the following

products were formed per each 100 mols of butane cracked:

Hydrogen	Methane	Ethylene	Ethane	Propylene	Propane
Mols	Mols	Mols	Mols	Mols	Mols
48.18	10.29	15.50	30.28	50.07	7.75

Iso-butylene	Normal butylene
Mols	Mols
2.93	28.39

It is seen from the above experiments that when no homogeneous catalyst is present in the reaction zone, as in "Run 1," only 47.5% by weight of normal butane is converted into propylene and butylene, whereas "Run 2" and "Run 3" show that when chromium naphthenate or tin naphthenate are present in the reacting zone 61.8% and 66.5% by weight, respectively, of the normal butane is converted into propylene and butylenes. Examination of the experimental data also shows that chromium naphthenate and/or tin naphthenate greatly increase the amount of straight dehydrogenation which occurs in the reacting zone; i. e., when chromium naphthenate was present 26.49 mols of butylenes were formed per each 100 mols of normal butane decomposed, and when tin naphthenate was present in the reacting zone 31.32 mols of butylenes were formed per 100 mols of normal butane decomposed, whereas "Run 1" shows that when no materials are added to the butane charge undergoing thermal decomposition only 11.89 mols of butylenes are formed per 100 mols of normal butane decomposed.

The catalytically produced olefins may be used in the manufacture of high octane gasoline or aviation fuel by polymerization of the unsatu- 40

rates in the hydrocarbons conversion mixture issuing from the reaction tubes. The reaction mixture may be cooled, condensed, then fractionated in order to remove therefrom any hydrogen, 5 methane, ethane, or ethylene and the fractionated product subjected to conventional processes of polymerization to form high octane gasoline blending material. It is also possible to effect a removal of the butylene from the effluent cracked 10 gases and subject such butylene to alkylation reactions for the purpose of producing iso-octane, which is a valuable anti-knock motor fuel blending material.

It is to be understood that the details of the 15 above examples are illustrative rather than limiting and that various modifications may be employed and practiced without departing from the essence of my invention as defined by the scope of the appended claims.

This is a continuation of my application Serial No. 375,013, filed January 18, 1941, for "Catalysts for dehydrogenating hydrocarbons."

I claim as my invention:

1. A process for dehydrogenating low molecular weight hydrocarbons, which comprises: subjecting said hydrocarbons to elevated cracking temperatures in the presence of tin naphthenate.

2. A process for increasing the yield of unsaturated hydrocarbons obtained when hydrocarbons are thermally decomposed, which comprises: forming a stream of said hydrocarbons substantially free from free hydrogen; adding an organic acid derivative of tin to said stream, and subjecting said stream carrying said derivative to a temperature sufficient to cause said thermal decomposition.

3. A process as in claim 2, in which the organic acid derivative is a tin naphthenate.

ROBERT G. ATKINSON.
